(57) **ABSTRACT**

An electric compressor includes a housing, refrigerant inlet port, a refrigerant outlet port, an inverter section, a motor section, a compression device and a front cover. The housing defines an intake volume and a discharge volume. The refrigerant inlet port is coupled to the housing and is configured to introduce the refrigerant to the intake volume. The compression device is a compression device configured to compress the refrigerant. The refrigerant outlet port is coupled to the housing and is configured to allow compressed refrigerant to exit the electric compressor from the discharge volume.

ELECTRIC SCROLL COMPRESSOR

FIELD OF THE INVENTION

The invention relates generally to electric compressors, and more particularly to an electric compressor that compresses a refrigerant using a scroll compression device.

BACKGROUND OF THE INVENTION

Compressors have long been used in cooling systems. In particular, scroll-type compressors, in which an orbiting scroll is rotated in a circular motion relative to a fixed scroll to compress a refrigerant, have been used in systems designed to provide cooling in specific areas. For example, such scroll-type compressors have long been used in the HVAC systems of motor vehicles, such as automobiles, to provide air-conditioning. Such compressors may also be used, in reverse, in applications requiring a heat pump. Generally, these compressors are driven using rotary motion derived from the automobile's engine.

With the advent of battery-powered or electric vehicles and/or hybrid vehicles, in which the vehicle may be solely powered by a battery at times, such compressors must be driven or powered by the battery rather than an engine. Such compressors may be referred to as electric compressors.

In addition to cooling a passenger compartment of the motor vehicle, electric compressors may be used to provide heating or cooling to other areas or components of the motor vehicle. For instance, it may be desired to heat or cool the electronic systems and the battery or battery compartment, when the battery is being charged, especially during fast charging modes, as such generate heat which may damage or degrade the battery and/or other system. It may also be used to cool the battery during times when the battery is not being charged or used, as heat may damage or degrade the battery. Since the electric compressor may be run at various times, even when the motor vehicle is not in operation, such use, obviously, requires electrical energy from the battery, thus reducing the operating time of the battery. Additionally, electric compressors may run at a very high speed, e.g., 2,000 RPM (or higher). Such high speed may generate unwanted levels of noise.

Some electric compressors may include a power or inverter circuit and/or other electronic circuits. The housing of the electric compressor may include a separate cavity for isolation and protecting such circuits that is at least partially formed by an aluminum cover. The cavity must protect, as well as electrically insulate, the circuitry. The aluminum cover is generally heavy and may contribute to the generation of noise.

Such scroll-type compressors may be driven using an electric motor, such as a three-phase alternating current (AC) motor. The electric motor may be located within a housing of the compressor and surrounded by the coolant. The windings of the electric motor must then pass through the coolant to be connected to a drive circuit which may be located internal or external to the compressor. Such an arrangement may be subject to current leakage and/or loss.

It is thus desirable, to provide an electric compressor having high efficiency, low-noise and maximum operating life. The present invention is aimed at one or more of the problems or advantages identified above.

BRIEF SUMMARY OF THE INVENTION

In a first aspect of the present invention, an electric compressor configured to compress a refrigerant is provided.

2

The electric compressor includes a housing, an inverter module, a motor, a compression device and an inverter protective layer. The housing defines an intake volume and a discharge volume and has a generally cylindrical shape and a central axis. The housing further includes an inverter housing. The inverter module is mounted to the inverter housing and is adapted to convert direct current electrical power to alternating current electrical power. The motor is mounted inside the housing. The compression device is coupled to the motor for receiving the refrigerant from the intake volume and compressing the refrigerant as the motor is rotated. The inverter protective layer is affixed to the inverter housing and encloses the inverter module.

In a second aspect of the present invention, an electric compressor configured to compress a refrigerant is provided. The electric compressor includes a housing, a refrigerant inlet port, and refrigerant outlet port, an inverter module, a motor, a drive shaft, a compression device, and an inverter protective layer. The housing defines an intake volume and a discharge volume and has a generally cylindrical shape and having a central axis. The housing includes an inverter housing. The refrigerant inlet port is coupled to the housing and configured to introduce the refrigerant to the intake volume. The refrigerant outlet port is coupled to the housing and configured to allow compressed refrigerant to exit the scroll-type electric compressor from the discharge volume. The inverter module is mounted to the inverter housing and adapted to convert direct current electrical power to alternating current electrical power. The motor is mounted inside the housing. The drive shaft is coupled to the motor. The compression device is coupled to the drive shaft for receiving the refrigerant from the intake volume and compressing the refrigerant as the drive shaft is rotated by the motor. The inverter protective layer is affixed to the inverter housing and encloses the inverter module therein.

In a third aspect of the present invention, an electric compressor configured to compress a refrigerant is provided. The electric compressor includes a housing, an inverter module, a motor, a compression device, and an inverter protective layer. The housing defines an intake volume and a discharge volume and has a generally cylindrical shape and a central axis. The housing includes a center housing and an inverter housing. The inverter housing is fastened to the center housing by a plurality of fasteners. The inverter module is mounted to the inverter housing and is adapted to convert direct current electrical power to alternating current electrical power. The inverter module includes a inverter circuit and a printed circuit board. The inverter circuit includes a plurality of power transistors mounted to the printed circuit board. The plurality of power transistors are connected to the inverter housing. The inverter housing includes a plurality of slots. Each slot is configured to receive a respective one of the power transistors. The inverter housing forms a heatsink for the plurality of power transistors. The motor is mounted inside the housing. The compression device is coupled to the motor for receiving the refrigerant from the intake volume and compressing the refrigerant as the motor is rotated. The inverter protective layer is affixed to the inverter housing and encloses the inverter module.

In a fourth aspect of the present invention, a method associated with an electric compressor configured to compress a refrigerant is provided. The electric compressor includes a housing, a motor, and a compression device. The housing defining an intake volume and a discharge volume, the housing having a generally cylindrical shape and having a central axis. The housing includes an inverter housing. The

inverter module is adapted to convert direct current electrical power to alternating current electrical power. The motor is mounted inside the housing. The compression device is coupled to the motor for receiving the refrigerant from the intake volume and compressing the refrigerant as the motor is rotated. The method includes the steps of: assembling the inverter module, mounting the inverter module to the inverter housing to form an inverter assembly, and forming an inverter protective layer around the inverter assembly.

BRIEF DESCRIPTION OF THE SEVERAL VIEWS OF THE DRAWINGS

These and other features and advantages of the present invention will become more readily appreciated when considered in connection with the following detailed description and appended drawings.

FIG. 18B is a second perspective view of the portion of the compression device of FIG. 18A.

FIG. 18C is a first perspective view of the fixed scroll of the compression device of FIG. 13.

FIG. 18D is a second perspective view of the fixed scroll of the compression device of FIG. 13.

FIG. 18E is a third perspective view of the fixed scroll of the compression device of FIG. 13.

FIG. 18F is a perspective view of a reed mechanism associated with the compression device of FIG. 13.

FIG. 19A is a first perspective view of a front cover of an electric compressor forming an oil separator, according to an embodiment of the present invention.

FIG. 19B is a second perspective view of the front cover of FIG. 19A.

FIG. 20 is a first perspective view of a front cover of an electric compressor forming an oil separator, according to a second embodiment of the present invention.

FIG. 21 is a top-down view of an electric motor of an electric compressor.

FIG. 22A is a first perspective view of an electric motor of an electric compressor, according to an embodiment of the present invention.

FIG. 22B is a second perspective view of the electric motor including three motor assemblies, according to a first embodiment of the present invention.

FIG. 22C is a wiring diagram associated with the electric motor of FIG. 22A, according to an embodiment of the present invention.

FIG. 23A is first perspective view an electric compressor with an inverter protective layer, according to an embodiment of the present invention.

FIG. 23B is a second perspective view of the electric compressor of FIG. 23A.

FIG. 24A is a first perspective view of the inverter protective layer of FIG. 23A.

FIG. 24B is an exploded view of a portion of the electric compressor of FIG. 23A.

FIG. 25A is a perspective view of a portion of the electric compressor of FIG. 23A.

FIG. 25B is a second exploded view of a portion of the electric compressor of FIG. 23A.

FIG. 26A is a perspective view of a portion of the inverter protective layer of FIG. 23A.

FIG. 26B is a perspective view of a portion of an inverter housing of the electric compressor of FIG. 23A.

FIG. 27A is a first cross-sectional view of a portion of the electric compressor of FIG. 23A, according to an embodiment of the present invention.

FIG. 27B is a second cross-sectional view of a portion of the electric compressor of FIG. 23A, according to an embodiment of the present invention.

FIG. 27C is a third cross-sectional view of a portion of the electric compressor of FIG. 23A, according to an embodiment of the present invention.

FIG. 28 is a fourth cross-sectional view of a portion of the electric compressor of FIG. 23A, according to an embodiment of the present invention.

FIG. 29 is a fifth cross-sectional view of a portion of the electric compressor of FIG. 23A, according to an embodiment of the present invention.

FIG. 30A is a graphical representation of a portion of an inverter module, according to an embodiment of the present invention.

FIG. 30B is a graphical representation of a cross-sectional view of a electric compressor including a portion of the inverter module of FIG. 30A.

DETAILED DESCRIPTION OF THE INVENTION

Referring to the figures, wherein like numerals indicate like or corresponding parts throughout the several views, an electric compressor 10 having an outer housing 12 is provided. The electric compressor 10 is particularly suitable in a motor vehicle, such as an automotive vehicle (not shown). The electric compressor 10 may be used as a cooling device or as a heating pump (in reverse) to heat and/or cool different aspects of the vehicle. For instance, the electric compressor 10 may be used as part of the heating, ventilation and air conditioning (HVAC) system in electric vehicles (not shown) to cool or heat a passenger compartment. In addition, the electric compressor 10 may be used to heat or cool the passenger compartment, on-board electronics and/or a battery used for powering the vehicle while the vehicle is not being operated, for instance, during a charging cycle. The electric compressor 10 may further be used while the vehicle is not being operated and while the battery is not being charged to maintain, or minimize the degradation, of the life of the battery. In the illustrated embodiment, the electric compressor 10 has a displacement of 57 cubic centimeters (cc). The displacement refers to the initial volume captured within the compression device as the scrolls of the compression device initially close or make contact (see below). It should be noted that the electric compressor 10 disclosed herein is not limited to any such volume and may be sized or scaled to meet particular required specifications.

In the illustrated embodiment, the electric compressor 10 is a compressor acts to compress a refrigerant rapidly and efficiently for use in different systems of a motor vehicle, for example, an electric or a hybrid vehicle. The electric compressor 10 may use a mixture of refrigerant and oil, throughout its operation, which may be referred to simply as "refrigerant".

The electric compressor includes 10 an inverter section 14, a motor section 16, and a compression device (or compression assembly) 18 contained within the outer housing 12. The outer housing 12 includes an inverter back cover 20, an inverter housing 22, a motor housing 24, a fixed scroll 26, and a front cover 28 (which may be referred to as the discharge head).

In a first aspect of the electric compressor 10 of the disclosure, an electric compressor 10 having a swing-link mechanism and drive shaft with an integrated limit pin is provided. In a second aspect of the electric compressor 10 of the disclosure, an electric compressor 10 with an oil separator is provided. In a third aspect of the electric compressor 10 of the disclosure, an electric compressor 10 having a scroll bearing oil injection, is provided. In a fourth aspect of

the electric disclosure of the disclosure, an electric compressor 10 having a bearing oil communication hole is provided. In a fifth aspect of the present invention, an electric compressor 10 having a domed inverter cover is provided.

In one embodiment, the inverter back cover 20, the inverter housing 22, the motor housing 24, a fixed scroll 26, and the front cover 28 are composed from machined aluminum. The inverter 10 may be mounted, for example, within the body of a motor vehicle, via a plurality of mount points 120.

General Arrangement, and Operation, of the Electric Compressor 10

The inverter back cover 20 and the inverter housing 22 form an inverter cavity 30. The inverter back cover 20 is mounted to the inverter housing 22 by a plurality of bolts 32. The inverter back cover 20 and the inverter housing 22 are mounted to the motor housing 24 by a plurality of bolts 34 which extend through apertures 36 in the inverter back cover 20 and apertures 38 in the inverter housing 22 and are threaded into threaded apertures 40 in the motor housing 24. An inverter gasket 42, positioned between the inverter back cover 20 and the inverter housing 22 keeps moisture, dust, and other contaminants from the internal cavity 30. A motor gasket 54A is positioned between the inverter housing 22 and the motor housing 24 to provide maintain a refrigerant seal to the environment.

With reference to FIG. 11, an inverter module 44 mounted within the inverter cavity 30 formed by the inverter back cover 20 and the inverter housing 22. The inverter module 44 includes an inverter circuit 46 mounted on a printed circuit board 48, which is mounted to the inverter housing 22. The inverter circuit 46 converts direct current (DC) electrical power received from outside of the electric compressor 10 into three-phase alternating current (AC) power to supply/power the motor 54 (see below). The inverter circuit 46 also controls the rotational speed of the electric compressor 10. High voltage DC current is supplied to the inverter circuit 46 via a high voltage connector 50. Low voltage DC current to drive the inverter circuit 46, as well as control signals to control operation of the inverter circuit 46, and the motor section 16, is supplied via a low voltage connector 52.

The motor section 16 includes a motor 54 located within a motor cavity 56. The motor cavity 56 is formed by a motor side 22A of the inverter housing 22 and an inside surface 24A of the motor housing 22. With specific reference to FIG. 12, the motor 54 is a three-phase AC motor having a stator 56. The stator 56 has a generally hollow cylindrical shape with six individual coils (two for each phase). The stator 56 is contained within, and mounted to, the motor housing 22 and remains stationary relative to the motor housing 22.

The motor 54 includes a rotor 60 located within, and centered relative to, the stator 58. The rotor 60 has a generally hollow cylindrical shape and is located within the stator 56. The rotor 60 has a number of balancing counterweights 60A, 60B, affixed thereto. The balancing counterweights balance the motor 54 as the motor 54 drives the compression device 18 and may be machined from brass.

Power is supplied to the motor 54 via a set of terminals 54A which are sealed from the motor cavity 56 by an O-ring 54B.

A drive shaft 90 is coupled to the rotor 60 and rotates therewith. In the illustrated embodiment, the draft shaft 90 is press-fit within a center aperture 60C of the rotor 60. The drive shaft 90 has a first end 90A and a second end 90B. The inverter housing 22 includes a first drive shaft supporting

member 22B located on the motor side of the inverter housing 22. A first ball bearing 62 located within an aperture formed by the first drive shaft supporting member 22 supports and allows the first end of the drive shaft 90 to rotate. The motor housing 24 includes a second drive shaft supporting member 24A. A second ball bearing 64 located within an aperture formed by the second drive shaft supporting member 24A allows the second end 90B of the drive shaft 90 to rotate. In the illustrated embodiment, the first and second ball bearing 62, 64 are press-fit with the apertures formed by the first drive shaft supporting member 22 of the inverter housing 22 and the second drive shaft supporting member 24A of the motor housing 24, respectively.

As stated above, the electric compressor 10 is a compressor. The compression device 18 includes the fixed scroll 26 and an orbiting scroll 66. The orbiting scroll 66 is fixed to the second end of the rotor 60B. The rotor 60 with the drive shaft 90 rotate to drive the orbiting scroll 66 motion under control of the inverter module 44 rotate.

With reference to FIGS. 14A, 14B, 16A and 16B, the drive shaft 90 has a central axis 90C around which the rotor 60 and the drive shaft 90 are rotated. The orbiting scroll 66 moves about the central axis 90C in an eccentric orbit, i.e., in a circular motion while the orientation of the orbiting scroll 66 remains constant with respect to the fixed scroll 26. The center of the orbiting scroll 66 is located along an offset axis 90D of the drive shaft 90 defined by an orbiting scroll aperture (or drive pin location 90E (see FIG. 14A) located at the second end 90B of the drive shaft 90. As the drive shaft 90 is rotated by the motor 54, the orbiting scroll 66 follows the motion of the orbiting scroll aperture 90E through the drive pin 162 and drive hub on the swinglink mechanism 124 and bearing 108 as the drive shaft 90 is rotated about the central axis 60C.

With specific reference to FIGS. 1, 2 and 9, intermixed refrigerant and oil (at low pressure) enters the electric compressor 10 via a refrigerant inlet port 68 and exits the electric compressor 10 (at high pressure) via refrigerant outlet port 70 after being compressed by the compression device 18. As shown in the cross-sectional view of FIG. 9, the refrigerant follows the refrigerant path 72 through the electric compressor 10. As shown, refrigerant enters the refrigerant inlet port 68 and enters an intake volume 74 formed between the motor side 22A of the inverter housing 22 and motor housing 24 adjacent the refrigerant inlet port 68. Refrigerant is then drawn through the motor section 16 and enters a compression intake volume 76 formed between an internal wall of the fixed scroll 26 and the orbiting scroll 66 (demonstrated by arrow 92 in FIG. 14A).

As shown in FIGS. 9 and 13, the fixed scroll 26 has a fixed scroll base 26A and a fixed scroll lap 26B extending away from the fixed scroll base 26A towards the orbiting scroll 66. As shown in FIGS. 16A-16B, the orbiting scroll 66 has an orbiting scroll base 66A and a orbiting scroll lap 66B extending from the orbiting scroll base 66A towards the fixed scroll 26. The laps 26A, 66A have a tail end 26C, 66C adjacent an outer edge of the respective scroll 26A, 66B and scroll inward towards a respective center end 26D, 66D.

Respective tip seals 94 are located within a slot 26E, 66E located at a top surface of the fixed scroll 26 and the orbiting scroll 66, respectively. The tip seals 94 are comprised of a flexible material, such as a Polyphenylene Sulfide (PPS) plastic. When assembled, the tip seals 94 are pressed against the opposite base 26A 66A to provide a seal therebetween. In one embodiment, the slots 26E 66E, are longer than the length of the tip seals 94 to provide room for adjustment/movement along the length of the tip seals 94.

With reference to FIGS. 17A-17I, intermixed refrigerant enters the compression device 12 from the compression intake volume 76. In FIGS. 17A-17I, a cross-section view of the fixed scroll 16 shown and the top of the orbiting scroll 66 are shown.

As discussed in detail below, the fixed scroll lap 16A and the orbiting scroll lap 66A form compression chambers 80 in which low or unpressurized (saturation pressure) refrigerant enters from the compression device 12. As the orbiting scroll 66 moves to enable the compression chambers 80 to be closed off and the volume of the compression chambers 80 is reduced to pressurize the refrigerant. At any one time during the cycle, one or more compression chambers 80 are at different stages in the compression cycle. The below description relates just to one set of compression chambers 80 during a complete cycle of the electric compressor 10.

The refrigerant enters the compression chambers 80 formed between the orbiting scroll lap 66A and the fixed scroll lap 26A. During a cycle of the compressor 10, the refrigerant is transported towards the center of these chambers. The orbiting scroll 66 orbits in a circular motion indicated by arrow 78 formed by the relative position of the orbiting scroll 66 relative to the fixed scroll 26 is shown during one cycle of the electric compressor 10.

In FIG. 17A, the position of the orbiting scroll 66 at the beginning of a cycle is shown. As shown, in this initial position, the tail ends 16B, 66B are spaced apart from the other scroll lap 66A 16. At this point, the compression chambers 80 are open to the compression intake volume 76 allowing refrigerant under low pressure to fill the compression chambers 80 from the compression intake volume 76. As the orbiting scroll 66 moves along path 78, the space between the tail ends 16A, 66A and the other scroll 66, 16 decreases until the compression chambers 80 are closed off from the compression intake volume 76 (FIGS. 17B-17E). As the orbiting scroll 66 continues to move along 78, the volume of the compression chambers 80 is further reduced, thus pressurizing the refrigerant in both compression chambers 80 (FIGS. 17F-H). As shown in FIGS. 17I-18J, as the orbiting scroll 66 continues to orbit, the two compression chambers 80 are combined into a single volume. This volume is further reduced until the pressurized refrigerant is expelled from the compression device 18 (see below).

As discussed below, the refrigerant enters chambers formed between the walls of the orbiting scroll 66 and the fixed scroll 26. During the cycle of the compressor 10, the refrigerant is transported towards the center of these chambers. The orbiting scroll 66 orbits or moves in a circular motion indicated by arrow 78 formed by the relative position of the orbiting scroll 66 relative to the fixed scroll 26 is shown during one cycle of the electric compressor 10.

Returning to FIG. 1, the front cover 28 forms a discharge volume 82. The discharge volume 82 is in communication with the refrigerant output port 70. As discussed in more detail below, pressurized refrigerant leaves the compression device 18 through an orifice 84 in the fixed scroll 26 (see FIGS. 18C and 18E). The release of pressurized refrigerant is controlled by a reed mechanism 86. In the illustrated embodiment, a single reed mechanism 86 is used. However, it should be noted that more than one reed mechanisms may be used.

As shown in FIGS. 18D and 18E, in the illustrated embodiment, the reed mechanism 86 includes a discharge reed 86A and a reed retainer 86B. The discharge reed 86A is made from a flexible material, such as steel. The characteristics, such as material and strength, are selected to control the pressure at which the pressurized refrigerant is

released from the compression device 18. The reed retainer 88B is made from a rigid, inflexible material, such as stamped steel. The reed retainer 866 controls or limits the maximum displacement of the discharge reed 86A relative to the fixed scroll 26.

In the illustrated embodiment, the read mechanism 86 is held or fixed in place without a separate fastener. As shown in FIGS. 18E and 18F, the reed mechanism 86 includes a pair of apertures 86C which are configured to receive associated posts 84A on the fixed scroll 26. When the electric compressor 10 is assembled, the reed mechanism 86 is adjacent, and held in place by, the front cover 28. As shown in FIG. 18E, the back surface of the fixed scroll 26 includes a bezel 84B surrounding the orifice 84 which assists in tuning the pressure at which refrigerant exits the compression device 18. Additionally, a debris collection slot 84B collects debris near the orifice 84 to prevent from interference with the reed mechanism 86.

As shown in FIG. 9, the path of refrigerant through the electric compressor is indicated by dashed arrow 72.

The electric compressor 10 utilizes oil (not shown) to provide lubrication to the between the components of the compression device 18 and the motor 54, for example, between the orbiting scroll 66 and the fixed scroll 26 and within the ball bearings 62, 64. The oil intermixes with the refrigerant within the compression device 18 and the motor 54 and exits the compression device 18 via the orifice 84. As discussed in more detail below, the oil is separated from the compressed refrigerant within the front cover 28 and is returned to the compression device 18.

An oil separator 96 facilitates the separation of the intermixed oil and refrigerant. Generally, the oil separator 96 only removes some of the oil within the intermixed oil and refrigerant. The separator oil is stored in an oil reservoir and cycled back through the compression device 18, where the oil is mixed back in with the refrigerant.

In the illustrated embodiment, the oil separator 96 is integrated within the front cover 28. The front cover 28 further defines an oil reservoir 98 which collects oil from the oil separator 96 before the oil is recirculated through the motor 54 and motor cavity 56 and the compression device 18. In use, the electric compressor 10 is generally orientated as shown in FIGS. 3-5, such that gravity acts as indicated by arrow 106 and oil collects within the oil reservoir 98. With reference to FIG. 9, the general path oil travels from the bottom of the electric compressor 10 through the compression device 18, out the orifice 84 to the discharge volume 82 of the front cover 28 and back to the compression device 18 is shown by arrow 88. As shown, the oil is drawn back up into the compression device 18 where the oil is mixed back into or with the refrigerant.

As stated above, refrigerant, which is actually a mixture of refrigerant and oil enters the electric compressor 10 via the refrigerant inlet port 68. The intermix of oil and refrigerant is drawn into the motor section 16, thereby providing lubrication and cooling to the rotating components of the electric compressor 10, such as the rotor 60, the drive shaft 90. Oil and refrigerant enters the interior of the motor 54 to lubricate the second ball bearing 64 and the oil by the rotational forces within the motor section 16. Oil may impact against the motor side 22A of the inverter housing 22. The refrigerant and oil is further directed by the motor side 22A into the ball bearing 62, further discussed below.

In the illustrated embodiment, the front cover 28 and the fixed scroll 26 are mounted to the motor housing 24 by a plurality of bolts 122 inserted through respective apertures therein and threaded into apertures in the motor housing 24.

A fixed head gasket 110 and a rear heard gasket 112, are located between the motor housing 24 and the fixed scroll 26 to provide scaling.

5 Swing-Link Mechanism and Concentric Protrusion of the Drive Shaft

With specific reference to FIGS. 13-18B, in a first aspect of the electric compressor 10 of the disclosure, an electric compressor 10 includes a swing link mechanism 124 and the drive shaft 90 has a concentric protrusion 90F. In one 10 embodiment, the concentric protrusion 126 is integrally formed with the drive shaft 90. As discussed below, the swing-link mechanism 124 is used to rotate the orbiting scroll 66 in an eccentric orbit about the drive shaft 90.

In the prior art, the drive shaft is coupled to a swing-link 15 mechanism by a drive pin and a separate eccentric pin, both of which are pressing into the drive shaft. The drive pin is used to rotate the swing link mechanism 124 which moves the orbiting scroll 66 along its eccentric orbit. The drive pin and the eccentric pin are inserted into respective apertures in 20 the end of the drive shaft. The eccentric pin is used to limit articulation of the orbiting scroll 66 is the orbiting scroll 66 travels along the eccentric orbit. Neither the drive pin, nor the eccentric pin, are located along the central axis of the drive shaft. As the drive shaft is rotated, the drive pin and the eccentric pin are placed under considerable stress. Thus, 25 both pins are composed from a hardened material, such as, SAE 52100 bearing steel. In addition, the eccentric pin may require an aluminum bushing or other slide bearing to prevent damage to the eccentric pin, as the eccentric pin is used to limit the radial movement of the eccentric orbit of 30 the orbiting scroll 66. Also, the prior art eccentric pin requires additional machining on the face of the drive shaft 90, including precise apertures for the drive pin, and eccentric pin.

35 As discussed in more detail below, the eccentric pin of the prior art is replaced with a concentric protrusion 90F.

In the illustrated embodiment, the electric compressor 10 includes the housing 12, the refrigerant inlet port 68, the refrigerant outlet port 70, the drive shaft 90, the concentric protrusion 90F, the motor 54, the compression device 18, the swing link mechanism 124, a drive pin 126 and a ball bearing 108. The housing 12 defines the intake volume 74 and the discharge volume 82. The refrigerant inlet port 68 is coupled to the housing 12 and is configured to introduce the refrigerant to the intake volume 74. The refrigerant outlet port 70 is coupled to the housing 12 and is configured to allow compressed refrigerant to exit the electric compressor 10 from the discharge volume 82. The drive shaft 90 is located within the housing 12 and has first and second ends 50 90A, 90B. The drive shaft 90 defines, and is centered upon, a center axis 90C.

The concentric protrusion 90F is located at the second end 55 90B of the drive shaft 90 and is centered on the center axis 90C. The concentric protrusion 90F and extends away from the drive shaft 90 along the central axis 90C. The concentric protrusion 90F includes a drive pin aperture 90E. The motor 54 is located within the housing 12 and is coupled to the drive shaft 90 to controllably rotate the drive shaft 90 about the center axis 90C. The drive pin 126 is located within the drive pin aperture 90E and extends away from the drive shaft 90. The drive pin 126 is centered on the offset axis 90D. The offset axis is parallel to the center axis 90C.

60 The concentric protrusion 90F may further include an undercut 90G, and the outer surface may be surface hardened or after treated with a coating or bearing surface. The concentric pin 90F may be further machined simultaneously with the drive shaft 90.

11

As explained above, the compression device 18 includes the fixed scroll 26 and the orbiting scroll 66. The fixed scroll 26 is located within, and being fixed relative to, the housing 12. The orbiting scroll 66 is coupled to the drive shaft 90. The orbiting scroll 66 and the fixed scroll 26 form compression chambers 80 (see above) for receiving the refrigerant from the intake volume 74 and for compressing the refrigerant as the drive shaft 90 is rotated about the center axis 90C. The orbiting scroll 66 has an inner circumferential surface 66E.

The swing-link mechanism 124 is coupled to the drive shaft 90 and has first and second apertures 124A, 124B for receiving the concentric protrusion 90F and the drive pin 126. The swing-link mechanism 124 further includes an outer circumferential surface 124C.

The ball bearing 108 is positioned between, and adjacent to each of, the inner circumferential surface 66E of the orbiting scroll 66 and the outer circumferential surface 124C of the swing-link mechanism 124. The drive shaft 90, drive pin 126, orbiting scroll 66 and swing-link mechanism 124 are arranged to cause the orbiting scroll 66 to rotate about the central axis 90C in an eccentric orbit.

In one embodiment, the concentric protrusion 90F is integrally formed with the drive shaft 90. The drive shaft 90, concentric protrusion 90F, and swing-link mechanism 124 may be machined from steel. The concentric protrusion 90F being formed simultaneously and within the same machining operation with the drive shaft 90 further increases manufacturing efficiencies.

The expanded view of a portion of the compression device 18 illustrated in FIG. 16G, further illustrates the concentric protrusion 90F. The concentric protrusion 90F interacts and guides the swing-link mechanism 124. The concentric protrusion 90F is sized and machined with a controlled tolerance with the first aperture 124A to create a controlled gap that limits the radial movement of the eccentric orbit of the orbiting scroll 66. Unlike the prior art, the concentric protrusion 90F does not require a second pin, or any additional machining operations. The concentric protrusion 90F further co-operates with the guidance pins 128 and the slots 66G on a lower surface 66F of the orbiting scroll 66, further discussed below.

The electric compressor 10 includes an inverter section 14, a motor section 16, and the compression device 18. The motor section 16 includes a motor housing 54 that defines a motor cavity 56. The compression section 18 includes the fixed scroll 26. The housing 12 is formed, at least in part, the fixed scroll 26 and the motor housing 24.

With specific reference to 13, 16B, and 18A-18F in the illustrated embodiment, the orbiting scroll 66 has a lower surface 66F. The lower surface 66F has a plurality of ring-shaped slots 66G. The motor housing 24 includes a plurality of articulating guidance pin apertures 128. The guidance pins 128 are located within the guidance pin apertures 66G and extend towards the compression device 18 and into the ring-shaped slots 66G. The guidance pins 128 are configured to limit articulation of the orbiting scroll 66 as the orbiting scroll 66 orbits about the central axis 90C. In one embodiment, each of the ring-shaped slots 66G includes a ring sleeve 118. A thrust plate 130 is located between motor housing 24 and the fixed scroll 26 and provides a wear surface therebetween.

Discharge Head Design Having an Oil Separator

In a second aspect of the electric compressor 10 of the disclosure, an electric compressor 10 includes an oil separator 96 located in the discharge volume 82, which may be located in the discharge volume 82 and integrally formed

12

with the discharge head or front cover 28. As discussed above, oil is used to provide lubrication between the moving components of the electric compressor 10. During operation, the oil and the refrigerant become mixed. The oil separator 96 is necessary to separate some of the oil from the mixture of the oil and refrigerant before the refrigerant leaves the electric compressor 10.

Generally, refrigerant is released from the compression device 18 once per revolution (or orbit) of the orbiting scroll 10 66. This creates a first order pulsation within the compressed refrigerant released by the electric compressor 10. The relative strong amplitude and low frequency of the pulsation creating in the refrigerant may excite other components (internal or external to the electric compressor 10) which may create undesirable noise, vibration and harshness (NVH) and low durability conditions. The oil separator 96 of the second aspect (described below), connects the discharge chambers (see below) by relatively small channels to create 15 pressure drops between the chambers. This acts to smooth 20 out the flow of compressed refrigerant out of the electric compressor 10. Additionally, the oil separator 96 utilizes two parallel paths between the compression device 18 and the refrigerant outlet port 70 to reduce the net pressure drop 25 while maintaining the reduction in this pulsation.

The oil separator 96 may include a series of partitions 98A extending from an inner surface of the front cover 28. As shown, the walls 98A separate the discharge volume 82 into a central discharge chamber 82A, two side discharge chambers 82B, an upper discharge chamber 82C and the oil reservoir 98. The central discharge chamber 82A is adjacent the reed mechanism 86 and receives intermixed pressurized refrigerant and oil from the compression device 18 through the slot 84 via the reed mechanism 86. The central discharge chamber 82 is in fluid communication with the two side discharge chambers 82B via respective side channels 100 which are in fluid communication with the upper discharge chamber 82C and the oil reservoir 98 via upper discharge channels 102 and lower discharge channels 104, respectively.

In the illustrated embodiment, the oil separator 96 is formed within the discharge chamber 82 of the housing 12 between the compression device 18 and the refrigerant outlet port 70. As shown, the oil separator 96 includes a central discharge chamber 82A, a pair of side discharge chambers 82B, an oil reservoir 98 and an upper discharge chamber 82C. The central discharge chamber 82A is formed adjacent the compression device outlet port or slot 84 for receiving the intermixed oil and compressed refrigerant. The pair of side discharge chambers 82B are located on opposite sides of the central discharge chamber 82A and are connected to the central discharge chamber 82A via respective side discharge channels 100.

The side chambers 82B are configured to separate the intermixed oil and compressed refrigerant. Generally, the intermixed oil and compressed refrigerant exit the central discharge chamber 82 through the side channels 100 at a high velocity. Separation of the oil and compressed refrigerant occurs as the intermixed oil and compressed refrigerant hits the interior outer wall of the respective side chambers 82B.

The oil reservoir 98 is located below the pair of side chambers and is connected thereto via the respective lower discharge channels 104. The oil reservoir is configured to receive oil separated from the compressed refrigerant in the side chambers. Gravity acting on the oil assists in the

separation and the oil falls through the lower discharge channels **104** located in the side discharge chambers **82B** into the oil reservoir **98**.

The upper discharge chamber **82C** is formed above the pair of side chambers **82B** and is connected thereto via the respective upper discharge channels **102**. Refrigerant, after being separated from the oil, rises through the upper discharge channels **102**, located at the top of the side discharge chambers **82** and enters the upper discharge chamber **82** before passing through the refrigerant outlet port **70**,

As shown, each side discharge channel **100** is configured to direct the intermixed oil and compressed refrigerant towards an opposite interior wall of the respective side channel **82B**. For instance, the side discharge channel is generally at a 90-degree angle from the opposite wall of the side discharge chamber **82B**.

In an alternative embodiment, as shown in FIG. 20, each side discharge chamber **82B** may include a side baffle **132** located within an interior portion of the respective side chamber **82B**. The side discharge channels **100** are configured to direct the intermixed oil and compressed refrigerant towards a respective side baffle. The side baffle **132** creates, on the back side opposite the discharge channels **100**, a low-pressure area within the side discharge chambers **82B** which assists in the separation of the oil and refrigerant. The low-pressure area may further assist gravity and reduce the oil from being carried upwards toward the upper discharge channels **102**. The side discharge channels **100** may incorporate a downward angle that may further assist the gravity forces on the oil and by directing the discharge of the mixture toward a lower area of the side discharge chamber **82B**, adjacent to the lower discharge channel **104**, to further increase the distance for the oil to fall out of the compressed mixture, and by creating a longer tortuous path to separate the oil downward and away from the high velocity compressed refrigerant entering into the upper discharge channels **102**. Also, the side baffles **132** may be arranged to create an impact surface perpendicular to the angled discharge flow path of the oil and refrigerant exiting from the side discharge channel **100**. The perpendicular impact surface on the side baffles **132** creates additional turbulence to the discharging mixture and with the lower pressure area behind the side baffles **132** may further increase the gravitational effect on the heavier oil to separate within and direct the oil into the lower discharge channel **104**.

Additionally, as shown in FIG. 20, the oil reservoir **98** may include an oil reservoir baffle **134** located beneath each lower discharge channel **104**. The oil reservoir baffle **134** assists in preventing oil within the oil reservoir **98** from being drawn out of the oil reservoir back into the side discharge chambers **82B**. The side baffle **132** and the oil reservoir baffle **134** may be used in combination or separately to reduce the oil from traveling upwards along the walls of the side discharge chamber **82B**, and by creating the low-pressure side further reducing the draw or venturi effect that may be created due to the high velocity flow of the refrigerant exiting through the upper discharge channel **102**.

Scroll Bearing Oil Orifice

In a third aspect of the electric compressor **10** of the disclosure, an electric compressor **10** having a scroll bearing oil injection orifice is provided. As discussed above, the compression device **18** of the present disclosure includes a ball bearing **108**. In the illustrated embodiments, the ball bearing **108** is located between the swing-link mechanism **124** and the orbiting scroll **66**. However, as a result of the location of the ball bearing **108** within the compression

device **18**, there may be limited oil delivery to the ball bearing **108** resulting in reduced durability.

The electric compressor **10** may include a housing **12**, a refrigerant inlet port **68**, a refrigerant outlet port **70**, an inverter module **144**, a motor **54**, a drive shaft **90** and a compression device **18**. The housing **12** defines an intake volume **74** and a discharge volume **82**. The refrigerant inlet port **68** is coupled to the housing **12** and is configured to introduce the refrigerant to the intake volume **74**. The refrigerant outlet port **70** is coupled to the housing **12** and is configured to allow compressed refrigerant to exit the electric compressor **10** from the discharge volume **82**. The inverter module **144** is mounted inside the housing **12** and adapted to convert direct current electrical power to alternating current electrical power. The motor **54** is mounted inside the housing **12**. The drive shaft **90** is coupled to the motor **54**. The compression device **18** receives the refrigerant from the intake volume **74** and compresses the refrigerant as the drive shaft **90** is rotated by the motor **54**. The compression device **18** includes a fixed scroll **26**, an orbiting scroll **66**, a swing-link mechanism **124**, a ball bearing **108** and a pin **136**.

The fixed scroll **26** is located within, and is fixed relative to, the housing **12**. The orbiting scroll **66** is coupled to the drive shaft **90**. The orbiting scroll **66** and the fixed scroll **26** form compression chambers **80** for receiving the refrigerant from the intake volume **72** and compressing the refrigerant as the drive shaft **90** is rotated about the center axis **90C**. The orbiting scroll **66** has a first side (or the lower surface) **66F** and a second side (or upper surface) **66G**. The orbiting scroll **66** has an oil aperture **140** through the orbiting scroll **66** from the first side **66F** to the second side **66G**.

The swing-link mechanism **124** is coupled to the drive shaft **90**. The ball bearing **108** is positioned between and adjacent to each of the orbiting scroll **66** and the swing-link mechanism **124**. The drive shaft **90**, orbiting scroll **66** and swing-link mechanism **124** are arranged to cause the orbiting scroll **66** to orbit the central axis **90C** in an eccentric orbit.

As shown in FIG. 16C, the tip of the orbiting scroll **66** includes a plug **136** and has an oil orifice **138**. The plug **136** may be press fit within the oil aperture **140** of the orbiting scroll **66**. The oil orifice **138** is configured to allow oil with a controlled flow rate or compressed refrigerant to pass through the orbiting scroll **66** to the ball bearing **108**.

The size of the oil orifice **138** may be tuned to the specifications of the electric compressor **10**. For example, given the specifications of the electric compressor **10**, the diameter of the oil orifice **138** may be chosen such that only oil is allowed to pass through and to limit the equalization of pressure between the first and second sides of the orbiting scroll **66**. By using a separate plug **136**, rather than machining the oil orifice **138** directly in the orbiting scroll **66**, manufacturing efficiencies may be achieved. And the plug **136** may have an oil orifice **138** that is specifically designed and tuned to allow for oil flow and refrigerant flow to increase or decrease depending on the diameter and geometry of the oil orifice **138**.

As shown in FIGS. 16D-16E, in one embodiment, the oil orifice **138** may have a first bore **138A** and a second bore **138B**, wherein a diameter of the first bore **138A** is less than a diameter of the second bore **138B**. For example, in one application of this embodiment the first bore **138A** has an approximate diameter of 0.3 mm. The second bore **138B** has a diameter greater than the diameter of the first bore **138A** and is only used to shorten the length of the first bore **138A**. The flow of the oil and coolant is designed to provide

thermal and lubricant to the ball bearing 108 supporting the radial forces created by the eccentric orbit of the orbiting scroll 66.

Further, as discussed above, the orbiting scroll 66 has an orbiting scroll base 66A and an orbiting scroll lap 66B. The orbiting scroll lap 66B may have an orbiting scroll tail end 66C and an orbiting scroll center end 66D. As shown, the oil aperture 140 is located within the orbiting scroll center end 66D. The plug 136 may be secured into the oil aperture 140, by press fit or any other method that will secure the plug 136.

As shown in FIG. 9, the oil orifice 138 allows oil (and refrigerant) to travel from the discharge chamber 82 to the ball bearing 108 along the bath 73 (which may be referred to as the "nose bleed" path).

Bearing Oil Communication Hole

In a fourth aspect of the electric disclosure of the disclosure, an electric compressor 10 having a bearing oil communication hole is provided. As discussed above, in the illustrated embodiment, a drive shaft 90 is rotated by the motor 54 to controllably actuate the compression device 18. The drive shaft 90 has a first end 90A and a second end 90B. The housing 10 of the electric compressor 10 forms a first drive shaft supporting member 22B and a second drive shaft support member 24A. In the illustrated embodiment, the first drive shaft supporting member 22B is formed in a motor side 22 of the inverter housing 22A and the second drive shaft supporting member 24A is formed within the motor housing 24. First and second ball bearings 62, 64 are located within the first and second drive shaft support members 22B, 24A.

The location of the first drive shaft supporting members 22B is not a flow-through area for refrigerant (and oil). This may result in a low lubricating condition and affect the durability of the electric compressor 10.

As shown in FIG. 16F, the first drive supporting member 22B may include one or more holes 22C to allow oil and refrigerant to enter the first drive support member 22B and lubricate the first ball bearing 62.

In the illustrated embodiment, the electric compressor 10 includes a housing 12, a first ball bearing 62, a second ball bearing 64, a refrigerant inlet port 68, a refrigerant outlet port 70, an inverter module 44, a motor 54, a drive shaft 90, and a compression device 18.

The housing 12 defines an intake volume 74 and a discharge volume 82 and includes first and second drive shaft supporting members 22B, 24A. The first ball bearing 62 is located within the first drive shaft supporting member 22B. The first drive shaft support member 22B of the housing 12 includes an oil communication hole 22C for allowing oil to enter the first ball bearing 62.

The second ball bearing 64 is located within the second drive shaft supporting member 24A. The refrigerant inlet port 68 is coupled to the housing 12 and is configured to introduce the refrigerant to the intake volume 74. The refrigerant outlet port 70 is coupled to the housing 12 and is configured to allow compressed refrigerant to exit the electric compressor 10 from the discharge volume 82. The inverter module 44 is mounted inside the housing 12 and is adapted to convert direct current electrical power to alternating current electrical power. The motor 54 is mounted inside the housing 12. The drive shaft 90 is coupled to the motor 54. The drive shaft 90 has a first end 90A and a second end 90B. The first end 90A of the drive shaft 90 is positioned within the first bearing 62 and the second end 90B of the drive shaft 90 is positioned within the second bearing 64. The compression device 18 receives the refrigerant from the intake volume 74 and compresses the refrigerant as the drive shaft 90 is rotated by the motor 54. As discussed above, in

the illustrated embodiment, the first drive shaft support member 22 may be formed on the motor side 22A of the inverter housing 22. The rotational movement within the motor section 16 of the compression device 18 creates a flow path and movement to the oil from the oil reservoir 98, as shown by arrows 88 in FIG. 9. As shown the oil flows from the oil reservoir 98 toward the motor section 16 and continues toward the stator 58 and rotor 60. The rotational motion of the orbiting scroll, rotor and drive shaft pulls the oil upward to mix with the inlet flow of the refrigerant path 72. The rotational movement of the rotor 60 and drive shaft 90 will further propel the oil against the motor side 22A of the inverter housing 22. The motor side 22A further includes a series of ribs 22D, shown in FIG. 16F. The ribs 22D provide the needed rigidity for supporting the first drive shaft support member 22 and allow for a ridged backing and pocket to secure the first bearing 62. The inverter housing 22 further defines an oil cavity 22E where oil collected between the ribs 22D is directed by gravity downward and into the oil cavity 22E. The ribs 22D and the sloped surface of the motor side 22A cooperate to capture and direct the oil splashed or propelled against the motor side 22A by the rotor 60 or drive shaft 90, to assist in increasing the oil flow into the oil cavity 22E and first bearing 62. FIG. 16F illustrates only one oil communication hole 22C, but it is appreciated additional oil communication holes 22C may be included above and between the ribs 22D on the motor side 22A of the inverter housing 22. For example, in the illustrated embodiment the communication hole 22C is 3.5 mm in diameter and the motor side 22A includes a sloping wall between the ribs 22D. In addition, the motor side 22A may include an outer oil collection area or depression 22F surrounding the communication holes 22C.

Domed Inverter Cover

In the fifth aspect of the electric compressor 10 of the present disclosure, an electric compressor 10 is configured to compress a refrigerant. The electric compressor 10 includes the housing 12, the refrigerant inlet port 68, the refrigerant outlet port 70, the inverter module 44, the motor 54, the drive shaft 90, the compression device 18 and the inverter cover 20. The housing 12 defines the intake volume 70 and the discharge volume 82. The housing 12 has a generally cylindrical shape and the central axis 90C. The refrigerant inlet port 68 is coupled to the housing 12 and is configured to introduce the refrigerant to the intake volume 70. The refrigerant outlet port 82 is coupled to the housing 12 and is configured to allow compressed refrigerant to exit the electric compressor 10 from the discharge volume 82.

The inverter module 44 is mounted inside the housing 12 and adapted to convert direct current electrical power to alternating current electrical power. The motor 54 is mounted inside the housing 12. The drive shaft 90 is coupled to the motor 54. The compression device 18 is coupled to the drive shaft 90 and is configured to receive the refrigerant from the intake volume and to compress the refrigerant as the drive shaft 90 is rotated by the motor 54.

As discussed above, the compression device 18 may rotate at a high speed (>2,000 RPM) which may create undesirable noise, vibration, and harshness (NVH) and low durability conditions. In the prior art, the inverter cover 20 is generally flat and tends to amplify and/or focus, the vibrations from the compression device 18.

As shown in FIGS. 3A-3D, to disperse vibrations rather than focus, the vibrations from the compression device 18, the inverter back cover 20 of the electric scroll-like compressor 10 of the fifth aspect of the disclosure is provided with a generally curved or domed profile.

As shown in the FIGURES, specifically FIGS. 1, 3A-3B and 6, the inverter cover 20 is located at one end of the electric compressor 10 and includes a first portion 20A and a second portion 20B. The first portion 20A includes an apex or apex portion 20C and is generally perpendicular to the central axis 90C and has an apex 20C and an outer perimeter 20D. The first portion 20A has a relatively domed-shaped such that the inverter cover 20 has a curved profile from the apex 20C towards the outer perimeter 20D. The amount and location of the curvature may be dictated or limited by other considerations, such as packaging constraints, i.e., the space in which the electric compressor 10 must fit, and constraints placed by internal components, i.e., location and size). The first portion 20A may also have to incorporate other features, e.g., apertures to receive fastening bolts. The second portion 20B may include a portion of the inverter cover 20 that is not domed, i.e., is relatively flat that is located about the perimeter of the inverter cover.

In FIG. 3B, the rear side of the inverter cover 20 may include a plurality radial ribs 20E extending outwardly from a center circular rib 20F to provide rigidity and support for the curved first portion 20A of the inverter back cover 20. As shown, the radial ribs 20E are not equally spaced about the center circular rib 20F. The inverter back cover 20 may also include additional ribs 20G to add additional strength.

With reference to FIGS. 3C and 3C, an alternative embodiment if the inverter cover 20 is shown. In some applications, the inverter cover 20, in particular, the first portion 20A may have to be modified to take into account external constraints, such as packaging or size restraints. In the illustrated embodiments, the illustrated embodiment includes a channel 20H that runs through the first portion 20A that is necessary to accommodate an external support structure.

Motor Connector Assembly

With reference to FIGS. 21, 22A-22H, and 23A-23G (in which like components are numbered the same as in the above embodiments), in one aspect of the present invention, the compressor 10 may include one or more motor connector assemblies 152. As discussed in more detail below, the motor connector assemblies 152 allows for quick, removable connection of the windings of the motor 54 to the inverter module 44. Further, the motor connector assembly 152 may be configured to allow the winding connections to be easily insulated to reduce or minimize electrical current leakage.

With particular reference to FIGS. 21, in the illustrated embodiment, the motor 54 is a three-phase AC motor 54. Each phase includes a plurality of windings 55, for example, four. In the illustrated embodiments, the first phase includes windings 55A-1, 55A-2, 55A-3, 55A-4; the second phase includes windings 55B-1, 55B-2, 55B-3, 55B-4, and the third phasing includes windings 55C-1, 55C-2, 55C-3, 55C-4. Electrically the windings 55 are connected serially in the following order: 55A-1, 55A-2, 55A-3, 55A-4, 55B-1, 55B-2, 55B-3, 55B-4, 55C-1, 55C-2, 55C-3, 55C-4 (see FIG. 22C). The junction between each phase 57 is connected to the PC board 48 via a respective connector assembly 152.

Inverter Protective Layer and Inverter Housing with Integral Heatsinks

With reference to FIGS. 23A-23B, 24A-24B, 25A-25B, 26A-26B, 27A-27C and 28, in which like components are numbered similarly, in another aspect of the present invention, the electric compressor 10 may include an inverter protective layer 170. The inverter protective layer 170 replaces the inverter back cover 20 discussed above. Generally, the inverter protective layer 170 may be formed using

a molding, potting or other process (see below) after at least a portion of the electric compressor 10 has been assembled and becomes integral or integrated with the inverter housing 22 and/or the electric compressor 10.

As discussed above, the electric compressor 10 generally includes a housing or outer housing 12. The housing 12 defines an intake volume 74 and a discharge volume 82. The housing 12 has a generally cylindrical shape with a central axis 90A. The housing 12 may including an inverter housing 22 that defines a portion of an inverter cavity 30. The inverter housing 22 may form one or more heatsinks (see below) for the inverter module 44 and/or inverter circuit 46.

In the illustrated embodiment of FIGS. 23A-23B, 24A-24B, 25A-25B, 26A-26B, 27A-27C and 28, the inverter cavity 30 is defined by the space containing the printed circuit board 48 and the inverter module 44 and/or inverter circuit 46. As discussed on more detail below. The printed circuit board 48 is fastened to the inverter housing 22 by a number of fasteners 178. The inverter protective layer 170 is formed using an associated assembly process after at least a portion of the electric compressor 10 is assembled.

In one embodiment, the inverter protective layer 170 may be composed of a polymeric based material and formed using an overmolding process. Generally, the inverter module 44 and/or each component of the inverter circuit 46 may be enclosed or surrounded by the inverter protective layer 170 for protection from the environment. The overmolding process may be a transfer molding process, a low pressure injection molding process or a similar process. Generally, such overmolding processes require a mold (not shown) that provides an outer shape to the inverter protective layer 170.

Alternatively, the inverter protective layer 170 may be formed using a potting process. Generally, the potting process may not require a mold.

In one embodiment, a first step the inverter module 44 is assembled, i.e., the inverter circuit 46 is assembled on the printed circuit board 48. In a second step, the inverter module 44 is attached or mounted to the inverter housing 22 by the fasteners 178. The combined inverter module and inverter housing 22 may be referred to as the inverter assembly 45. Then the inverter protective layer 170 may be formed around the inverter assembly 45.

If the inverter protective layer 170 is formed using an overmolding process, then the inverter assembly 45 may be placed within a mold (not shown) and overmolded with the polymeric based material. The polymeric based material flows over the inverter housing including the inverter assembly 45 thereby enclosing the printed circuit board 47 and the inverter circuit 46 filling all the gaps between the different components. The inverter assembly 45 may then be taken out of the mold. The overmold material adheres to the inverter assembly 45, including the components of the inverter circuit 46 and the inverter housing 22, so disassembly without breakage is not possible.

The inverter module 44 is mounted inside the inverter cavity 30 of the housing 12. As discussed above, the inverter module 44 is adapted to convert direct current electrical power to alternating current electrical power. The motor 54 is mounted inside the housing 12. The compression device 18 is coupled to the motor 54 and is configured to receive the refrigerant from the intake volume 74 and to compress the refrigerant as the motor 54 is rotated.

With reference to FIGS. 23A-23B, 24A-24B, 25A-25B, 26A-26B, 27A-27C and 28, the inverter protective layer 170 is affixed to the inverter housing 22. The inverter housing 22 and the inverter protective layer 200 form the inverter cavity

30. The inverter module 44 is enclosed with in the interior cavity 30 formed by the inverter housing 22 and the inverter protective layer 170.

In one aspect of the present invention, the inverter protective layer 170 is formed using an overmolded process after the inverter module 44 has been mounted to the inverter housing 22. As discussed above, the housing 12 includes a center housing 24. The inverter housing 24 is fastened to the inverter housing 22 by a plurality of fasteners 32. The inverter module 44 includes an inverter circuit 46 and a printed circuit board 48.

With specific reference to FIGS. 27C, 29, 30A and 30B, the inverter circuit 46 includes one or more power transistors 172. In the illustrated embodiment, the inverter circuit 46 includes six power transistors 172 which are designed for high-voltage, high-current applications. The power transistors 172 may be bipolar transistors with an insulated gate terminal which may be referred to as an insulated-gate bipolar transistor or IGBT.

As shown, the power transistors 172 are mounted to the printed circuit board 48. As discussed above, the inverter housing 22 may be composed from aluminum. In the illustrated embodiment, the power transistors 172 may be thermally connected to the inverter housing 22. As discussed above, the inverter housing 22 may be composed from aluminum. The inverter housing 22 acts as a heatsink for the power transistors 172. In one embodiment, the power transistor 172 may be connected to a inverter housing 22 via a thermal tape or paster. Alternatively or in addition, the power transistors 172 may be connected to the inverter housing 22 using a respective fastener 174. With particular reference to FIG. 30B, The printed circuit board 48 may include a respective access aperture 48A. Each power transistor 172 has a respective aperture 172A and the inverter housing includes a plurality of respective threaded aperture 22E. The fasteners 174, e.g., screws, may be inserted through the access apertures 48A in the printed circuit board 48 and the apertures 172A in the power transistors 172 and into the threaded apertures 22E in the inverter housing 22. As stated above, the power transistors 172 may be thermally connected to the inverter housing 22 may the thermal paste or tape and/or the fasteners 174.

Further, as shown in FIGS. 24B, 25B, 26B, the inverter housing 22 may further include a plurality of slots or cavities 22F for receiving the power transistors 172. The slots 22F may perform the heatsink function. With reference to FIG. 26B, the motor side 22A of the inverter housing 22 may include a plurality of pins or extensions 22G configured to increase the heat transfer between the inverter housing 22 and the refrigerant by increasing the exposed surface of the motor side 22A of the inverter housing 22 to the refrigerant.

As discussed above, the inverter housing 22 may include a first drive shaft supporting member 22B (see FIG. 26B), located on the motor side 22A on the inverter housing 22 for receiving a first ball bearing 62. In some embodiment, the plurality of power transistors 172 may positioned an equal distance from a center of the first drive shaft supporting member 22B. Further, the plurality of power transistors 172 may be organized in groups of one or more power transistors 172. The groups of power transistors 172 may be radially equally spaced about the center of the first drive shaft supporting member 22B. With specification reference to FIG. 30A, in the illustrated embodiment, the inverter circuit 46 includes six power transistors 172 organized in three groups of two transistors 172 each. The groups of power transistors 172 may be radially spaced about the center of the first drive shaft supporting member 22B 120° apart.

With particular reference to FIG. 29, the overmolded inverter 170 may include an embedded inverter liner or plate 176 to provided rigidity for protection as well as electromagnetic shielding. The embedded inverter liner or plate 176 may be composed from aluminum.

The foregoing invention has been described in accordance with the relevant legal standards, thus the description is exemplary rather than limiting in nature. Variations and modifications to the disclosed embodiment may become apparent to those skilled in the art and fall within the scope of the invention.

What is claimed is:

1. An electric compressor configured to compress a refrigerant, comprising:

a housing defining an intake volume and a discharge volume, the housing having a generally cylindrical shape and having a central axis, the housing including an inverter housing;

an inverter module mounted to the inverter housing and adapted to convert direct current electrical power to alternating current electrical power;

a motor mounted inside the housing;

a compression device, coupled to the motor, for receiving the refrigerant from the intake volume and compressing the refrigerant as the motor is rotated; and,

an inverter protective layer affixed to the inverter housing and enclosing the inverter module, wherein each component of the inverter module being enclosed within, and contacted by and surrounded by, the inverter protective layer, the inverter protective layer being formed using an overmolding process after the inverter module has been mounted to the inverter housing, the inverter protective layer forming, at least partly, an outer surface of the electric compressor.

2. The electric compressor, as set forth in claim 1, further including an embedded inverter liner fully enclosed, and affixed within, the inverter protective layer, the embedded inverter liner configured to provide electro-magnetic shielding.

3. The electric compressor, as set forth in claim 2, wherein the housing includes a center housing, the inverter housing being fastened to the center housing by a plurality of fasteners.

4. The electric compressor, as set forth in claim 1, wherein the inverter module includes an inverter circuit and a printed circuit board, the inverter circuit includes a power transistor mounted to the printed circuit board.

5. The electric compressor, as set forth in claim 4, wherein the power transistor is connected to the inverter housing, the inverter housing forming a heatsink for the power transistor.

6. The electric compressor, as set forth in claim 5, the inverter housing including at least one slot for receiving the power transistor.

7. The electric compressor, as set forth in claim 1, wherein the inverter module includes an inverter circuit and a printed circuit board, the inverter circuit includes a plurality of power transistors mounted to the printed circuit board.

8. The electric compressor, as set forth in claim 7, wherein the plurality of power transistors are connected to the inverter housing, the inverter housing forming a heatsink for the plurality of power transistors.

9. The electric compressor, as set forth in claim 8, the inverter housing including a plurality of slots, each slot configured to receive a respective one of the power transistors.

10. The electric compressor, as set forth in claim 7, the inverter housing including a first drive shaft supporting

21

member, wherein the plurality of power transistors are positioned an equal distance from a center of the first drive shaft supporting member.

11. The electric compressor, as set forth in claim 10, wherein the plurality of power transistors are organized in three groups of power transistors of at least one power transistor, the groups of power transistors being spaced 120° about the center of the first drive shaft supporting member.

12. An electric compressor configured to compress a refrigerant, comprising:

a housing defining an intake volume and a discharge volume, the housing having a generally cylindrical shape and having a central axis, the housing including an inverter housing;

a refrigerant inlet port coupled to the housing and configured to introduce the refrigerant to the intake volume;

a refrigerant outlet port coupled to the housing and configured to allow compressed refrigerant to exit the electric compressor from the discharge volume;

an inverter module mounted to the inverter housing and adapted to convert direct current electrical power to alternating current electrical power;

a motor mounted inside the housing;

a drive shaft coupled to the motor;

a compression device coupled to the drive shaft, for receiving the refrigerant from the intake volume and compressing the refrigerant as the drive shaft is rotated by the motor; and,

an inverter protective layer affixed to the inverter housing and enclosing the inverter module, wherein each component of the inverter module being enclosed within, and contacted by and surrounded by, the inverter protective layer, the inverter protective layer being formed using an overmolding process after the inverter module has been mounted to the inverter housing, the inverter protective layer forming, at least partly, an outer surface of the electric compressor.

13. The electric compressor, as set forth in claim 12, further including an embedded inverter liner fully enclosed, and affixed within, the inverter protective layer, the embedded inverter liner configured to provide electro-magnetic shielding.

14. The electric compressor, as set forth in claim 13, wherein the housing includes a center housing, the inverter housing being fastened to the center housing by a plurality of fasteners.

15. The electric compressor, as set forth in claim 12, wherein the inverter module includes an inverter circuit and a printed circuit board, the inverter circuit includes a power transistor mounted to the printed circuit board.

16. The electric compressor, as set forth in claim 15, wherein the power transistor is connected to the inverter housing, the inverter housing forming a heatsink for the power transistor.

17. The electric compressor, as set forth in claim 16, the inverter housing including at least one slot for receiving the power transistor.

18. The electric compressor, as set forth in claim 12, wherein the inverter module includes an inverter circuit and a printed circuit board, the inverter circuit includes a plurality of power transistors mounted to the printed circuit board.

19. The electric compressor, as set forth in claim 18, wherein the plurality of power transistors are connected to the inverter housing, the inverter housing forming a heatsink for the plurality of power transistors.

22

20. The electric compressor, as set forth in claim 19, the inverter housing including a plurality of slots, each slot configured to receive a respective one of the power transistors.

21. The electric compressor, as set forth in claim 18, the inverter housing including a first drive shaft supporting member, wherein the plurality of power transistors are positioned an equal distance from a center of the first drive shaft supporting member.

22. The electric compressor, as set forth in claim 10, wherein the plurality of power transistors are organized in three groups of power transistors of at least one power transistor, the groups of power transistors being spaced 120° about the center of the first drive shaft supporting member.

23. An electric compressor configured to compress a refrigerant, comprising:

a housing defining an intake volume and a discharge volume, the housing having a generally cylindrical shape and having a central axis, the housing including a center housing and an inverter housing;

an inverter module mounted to the inverter housing and adapted to convert direct current electrical power to alternating current electrical power, the inverter module including an inverter circuit and a printed circuit board, the inverter circuit including a plurality of power transistors mounted to the printed circuit board, the plurality of power transistors being connected to the inverter housing, the inverter housing including a plurality of slots, each slot configured to receive a respective one of the power transistors, the inverter housing forming a heatsink for the plurality of power transistors;

a motor mounted inside the housing;

a compression device, coupled to the motor, for receiving the refrigerant from the intake volume and compressing the refrigerant as the motor is rotated; and, an inverter protective layer affixed to the inverter housing and enclosing the inverter module therein, wherein each component of the inverter module being enclosed within, and contacted by and surrounded by, the inverter protective layer, the inverter protective layer being formed using an overmolding process after the inverter module has been mounted to the inverter housing, the inverter protective layer forming, at least partly, an outer surface of the electric compressor.

24. The electric compressor, as set forth in claim 23, the inverter housing including a first drive shaft supporting member, wherein the plurality of power transistors are positioned an equal distance from a center of the first drive shaft supporting member.

25. The electric compressor, as set forth in claim 23, wherein the plurality of power transistors are organized in three groups of power transistors of at least one power transistor, the groups of power transistors being spaced 120° about the center of the first drive shaft supporting member.

26. A method associated with an electric compressor configured to compress a refrigerant, the electric compressor including a housing, a motor, and a compression device, the housing defining an intake volume and a discharge volume, the housing having a generally cylindrical shape and having a central axis, the housing including an inverter housing, the inverter module adapted to convert direct current electrical power to alternating current electrical power, the motor being mounted inside the housing, the compression device being coupled to the motor for receiving the refrigerant from the intake volume and compressing the refrigerant as the motor is rotated, the method including the steps of:

assembling the inverter module;
mounting the inverter module to the inverter housing to
form an inverter assembly;
forming an inverter protective layer around the inverter
assembly, wherein each component of the inverter 5
module being enclosed within, and contacted by and
surrounded by, the inverter protective layer being
formed using an overmolding process after the inverter
module has been mounted to the inverter housing, the
inverter protective layer forming, at least partly, an 10
outer surface of the electric compressor.

27. The method, as set forth in claim 26, wherein the step
of forming the inverter protective layer, including the step of
placing the inverter assembly within a mold, wherein the
inverter protective layer is formed using an overmolding 15
process.
